(57) **CLAIM**

The ornamental design for a throttle for a patient support, as shown and described.

DESCRIPTION

FIG. 1 is a top front, right side, perspective view of a throttle for a patient support;

FIG. 2 is a top back, right side, perspective view thereof;

FIG. 3 is a top back, left side, perspective view thereof;

FIG. 4 is a top front, left side, perspective view thereof;

FIG. 5 is a front view thereof;

FIG. 6 is a back view thereof;

FIG. 7 is a left side view thereof;

FIG. 8 is a right side view thereof;

FIG. 9 is a top view thereof; and,

FIG. 10 is a bottom view thereof.

The broken lines throughout the figures depict portions of the throttle for a patient support that form no part of the claimed design.

1 Claim, 5 Drawing Sheets
